UNITED STATES PATENT OFFICE

149,557

DESIGN FOR A CARRIER FOR GOLF CLUBS

Arnold H. Jessen, Los Angeles, Calif.

Application November 2, 1946, Serial No. 134,472

Term of patent 3½ years

(Cl. D34—5)

To all whom it may concern:

Be it known that I, Arnold H. Jessen, a citizen of the United States of America and a resident of the city of Los Angeles, in the county of Los Angeles and State of California, have invented a new, original, and ornamental Design for a Carrier for Golf Clubs, of which the following is a specification, reference being had to the accompanying drawings, forming part thereof.

In the drawings:

Figure 1 is a front elevational view of a carrier for golf clubs, showing my new design.

Figure 2 is a top plan view thereof.

Figure 3 is a side elevational view thereof, and

Figure 4 is a view thereof taken substantially along line 4—4 of Figure 1.

I claim:

The ornamental design for a carrier for golf clubs, substantially as shown.

ARNOLD H. JESSEN.
